UNITED STATES PATENT OFFICE.

EUGENE H. CROWN, OF SACRAMENTO, CALIFORNIA, ASSIGNOR TO FLORY CARRY IRON COMPANY, OF ST. LOUIS, MISSOURI, A CORPORATION OF DELAWARE.

DRAW-BAR CARRY-IRON.

1,157,088.

Specification of Letters Patent.

Patented Oct. 19, 1915.

Application filed March 6, 1914. Serial No. 822,890.

To all whom it may concern:

Be it known that I, EUGENE H. CROWN, a citizen of the United States, residing at city of Sacramento, county of Sacramento, State 5 of California, have invented a certain new and useful Improvement in Draw-Bar Carry-Irons, of which the following is a full, clear, and exact description, such as will enable others skilled in the art to which it 10 appertains to make and use the same, reference being had to the accompanying drawings, forming part of this specification, in which—

Figure 1 is a front elevational view of a 15 railway car striking plate and showing my improved carry iron applied thereto. Fig. 2 is a vertical section taken on the line 2—2 of Fig. 1. Fig. 3 is a horizontal section taken approximately on the line 3—3 of 20 Fig. 1. Fig. 4 is a perspective view of my improved carry iron with the roller removed.

My invention relates to new and improved carrying means for the draw bar of car 25 couplers, the principal object of my invention being to provide a reversible bar or carrying member, and to combine therewith a roller which has a certain amount of backward and forward movement upon the supporting bar, and which roller supports the draw bar, thereby reducing to a minimum 30 the friction between the support and the draw bar, as the latter moves lengthwise as a result of pulling and buffing strains.

A further object of my invention is to provide a rolling support for draw bars which can be adjusted vertically so as to 35 vary the height at which the draw bar is carried.

With the above and other objects in view, my invention consists in certain novel features of construction and arrangement of parts, hereinafter more fully described and claimed.

Referring by numerals to the accompanying drawings, 1 designates a striking plate which is applied in the usual manner to the car end sill or buffer beam, and formed integral with or fixed to this striking plate are 45 depending brackets 2, the lower ends of which are bifurcated so as to receive the ends of my improved carry iron. The walls of one of these brackets are provided on their inner faces with substantially U-shaped 50 seats 3 which are adapted to receive trun-

nions formed on one end of my improved carry iron and the walls of the opposite bracket are perforated to receive a pin or bolt.

The main body of my improved carry iron 60 comprises a block 4, which is approximately rectangular in cross section and provided in its top and bottom faces with longitudinally disposed grooves or depressions 5. Formed integral with the ends of this block are 65 heads 6 which are adapted to fit snugly between the walls at the bifurcated lower ends of the brackets 2, and formed integral with the head at one end of the block are 70 trunnions 7 which, when the carry iron is properly positioned for use, occupy the seats 3. Formed through the opposite head 6 is an aperture 8 which, when the carry iron is 75 positioned for use, coincides with the apertures formed through the walls of one of the brackets 2, and positioned in these apertures is a locking pin or bolt 9. The carry iron is formed so that the bottom surfaces of the grooves or recesses 5 are located at 80 different distances from a horizontal line drawn through the centers of the trunnions 7 and the locking pin 9, and thus, by reversing the carry iron, the height at which the supported draw bar is carried can be varied.

Loosely mounted in the groove or recess 85 on top of the block 4 is a roller 10, the ends of which normally occupy positions between the walls at the lower ends of the brackets 2. The shoulders 6^a formed between the heads 90 6 and the block 4 holds the roller 10 against longitudinal movement, but said roller is free to roll backward and forward upon the block 4, thus forming a rolling support for the draw bar and reducing the friction between 95 said draw bar and support as the draw bar is moved lengthwise under pulling and buffing strains.

The backward and forward movement of the roller 10 is limited by the ribs or flanges 100 at the sides of the grooves 5, and as the ends of said roller project between the walls at the lower ends of the brackets 2, said roller is prevented from becoming accidentally displaced from the block 4, as a result of blows 105 or jars which may be received by the carry iron or striking plate.

By my improved construction of carry iron, a free rolling support is provided for the supported draw bar, the movement of 110

which rolling support is lengthwise of the car, and in the same direction as the pulling and buffing movements imparted to the draw bar. For this reason the friction between the draw bar and its support is reduced to a minimum.

By making the block 4 reversible, and forming the bottoms of the grooves or recesses at different distances from the horizontal center of said block the height at 10 which the supported draw bar is carried may be varied or adjusted.

It will be readily understood that minor changes in the size, form and construction 15 of the various parts of my improved draw bar carry iron may be made and substituted for those herein shown and described, without departing from the spirit of my invention, the scope of which is set forth in the 20 appended claims.

I claim:

1. The herein-described carry iron comprising an elongated member provided with a plurality of longitudinally disposed 25 grooves, the faces of which are arranged at different distances from the horizontal cen-

ter of said member, a roller loosely mounted in the uppermost one of said grooves, shoulders at the ends of said grooves for holding the roller against longitudinal movement, and ears on the ends of said member, which ears are adapted to be secured to suitable supports.

2. The herein-described carry iron comprising an elongated member provided with a plurality of roller seats arranged at different distances from its horizontal center, whereby the elevation of the uppermost seat can be varied by reversing the carry iron, a roller loosely mounted on the uppermost 35 seat, and ears on the ends of said carry iron, portions of which ears serve as shoulders to hold the roller against longitudinal movement.

In testimony whereof, I hereunto affix my 45 signature in the presence of two witnesses, this 21st day of February, 1914.

EUGENE H. CROWN.
